UNITED STATES PATENT OFFICE.

BRADY F. BECK, OF LOCK HAVEN, PENNSYLVANIA.

VENTILATING DEVICE FOR STORE-WINDOWS.

No. 927,317.

Specification of Letters Patent.

Patented July 6, 1909.

Application filed August 20, 1908. Serial No. 449,400.

To all whom it may concern:

Be it known that I, BRADY F. BECK, a citizen of the United States, and a resident of Lock Haven, in the county of Clinton and 5 State of Pennsylvania, have made certain new and useful Improvements in Ventilating Devices for Store-Windows, of which the following is a specification.

My invention relates to means for ventilating show windows of stores, and it consists in 10 the combinations, arrangements and constructions hereinafter described and claimed.

An object of my invention is to provide an 15 efficient means for preventing the frosting of store windows in cold weather. In regions of continued cold, great annoyance is caused by the accumulation of frost on the inside of a store window, thereby obscuring the view of the goods contained within the window. 20 The cause of the accumulation of frost on the window is the condensation and subsequent freezing of the moisture contained in the warm air of the room or store, this condensation being caused by the warm moisture-laden 25 air coming in contact with the cold window.

In carrying out my invention I provide a 30 ventilating means, whereby the inside of the window is constantly ventilated by means of a stream of cold dry air, which is played over the surface of the window and effectually prevents the warm moisture-laden air from 35 coming in contact therewith. This prevents the formation of frost, since the moisture does not have a chance to reach the cold window.

My invention is illustrated in the drawings, in which—

Figure 1 is a front view of the exterior of a 40 window provided with my invention. Fig. 2 is a perspective view of a section taken through the window and sash along the line 2—2 of Fig. 1, and Fig. 3 is a section showing a different form of the ventilating opening.

Referring now to Fig. 1, I have shown 45 therein a portion of a store window A, provided with upper and lower sash parts 1 and 2, respectively. Through the upper portion 1 of the sash I bore a series of holes 3. Each 50 of these holes is about three-quarters of an inch in diameter, and they are spaced approximately five inches apart. These holes are located above the edge of the glass as clearly shown in Fig. 2.

On the inner side of the upper part 1 of the 55 sash, I fasten a deflecting strip 4. This strip

may be in any convenient form, but is designed to deflect the air coming in through the opening 3 around the molding 5 and to spread it out along the surface of the glass 6. 60 This deflector 4 is attached to the sash by means of the screws 7, which pass through an upwardly extending flange 8.

Through the bottom sash strip 9 of the window, I bore a series of upwardly inclined 65 holes 10, which preferably pass through the molding 11, as shown in Fig. 2. Immediately above the upper end of this opening is the deflecting plate 12, which may be of a curved form as shown in Fig. 2, or, it may be 70 a flat, inclined strip as shown at 12' in Fig. 3, or it may have other convenient forms, the main object being to provide a deflecting plate which serves to spread out the air along the surface of the glass and at the same time 75 should present a neat and ornamental appearance.

In Fig. 2 I have shown the bottom sash member 9 as projecting above the line of the floor 13, the glass being held between the 80 member 9 and the molding 11. In Fig. 3 I have shown the arrangement where the glass is held between the flooring and the bottom member 9 of the sash. In this arrangement the inclined hole 10 meets a vertically extending hole 14, which is situated directly 85 underneath the deflecting plate 12'.

The operation of the device may be readily understood from the foregoing description of the various parts. The air enters through 90 the holes 3 and 10. The space between the deflecting members 12 and 2 and their respective moldings 5 and 11, provides a common air channel, in which the air coming through the holes is mixed and then passes 95 upwardly or downwardly, as the case may be, along the entire upper and lower edges of the glass plate 6, thereby preventing the warm moist air from coming in contact with the window. It will be noted that there is 100 a continuous opening along the entire edge of the glass plate between the latter and the deflector, so that the air is distributed evenly over the entire surface of the glass. I regard this as a very important feature of my invention, since, if it were permitted to be distributed at separate points as has been proposed, the frost is sure to gather on the window between the air ports as has been 105 proved by actual experience.

I claim—

In a window ventilator, upper and lower

window sash members, the upper sash member having a series of horizontal openings therethrough, a common deflector plate carried by said upper sash member forming a common channel in communication with said horizontal openings, the lower window sash having a series of inclined passages therethrough leading from the underside of the sash, a pane of glass carried by said window sash, a deflector plate secured to the floor of the window and forming a common

channel in communication with said inclined passages, the edges of said upper and lower deflector plates being in close proximity to the inner side of the pane of glass, thereby deflecting the in-coming air in continuous thin sheets toward the center of the window. 15

BRADY F. BECK.
